UNITED STATES PATENT OFFICE.

HARRY J. LEBHERZ AND ROBERT W. LEBHERZ, OF FREDERICK, MARYLAND, AS
SIGNORS TO THE EVEREDY COMPANY, OF FREDERICK, MARYLAND, A CORPORA-
TION OF MARYLAND.

BOTTLE-CAPPING TOOL.

Application filed January 4, 1927. Serial No. 158,908.

Our invention relates broadly to bottle capping tools and more particularly to an improved bottle capper having means for facilitating quick successive operations for applying a crown cap to a bottle.

One of the objects of our invention is to provide an arrangement of spring return for the operating lever of a bottle capping tool for elevating the capping head and 10 rider after each capping operation to a position for effecting a successive capping operation.

Another object of our invention is to provide an arrangement of spring return for 15 the operating lever of a bottle capping tool having a rider arranged to slidably engage a rack, wherein the spring return is directly effective upon a segment of the operating lever, which meshes with the rack for normally elevating the rider after each capping 20 operation.

Still another object of our invention is to provide a construction of spring bridge between a 25 bottle tool and the operating lever for successively elevating the operating lever and rider by cooperation of the operating lever with the vertical rack after each capping operation.

Our invention will be more clearly understood by reference to the following specification and the accompanying drawings wherein:

Figure 1 is a side elevation of the bottle capping tool of our invention showing the tool with operating lever in elevated position ready for the application of a crown cap to a bottle; Fig. 2 is a fragmentary view 35 of the bottle capping tool showing the operating lever moved to a position in which the crown cap is applied to the bottle; Fig. 3 is an enlarged cross-sectional view taken through the capping throat and showing the parts of the capping tool partially in side elevation, the operating lever being elevated 40 to its uppermost position; Fig. 4 is a cross-sectional view taken through the rider of the bottle capping tool on line 4-4 of Fig. 3; Fig. 5 is a cross-sectional view taken 45 through the bottle capping throat of the capping tool on line 5-5 of Fig. 3; Fig. 6 is a perspective view showing the device which we employ for retaining the crown cap in the capping throat preparatory to a

capping operation; and Fig. 7 is a view 55 showing parts of the rider and capping throat in cross section and illustrating a modified arrangement of spring return for the operating lever of the capping tool.

Our invention is directed to a simplified construction of a bottle capping tool which is an improvement over the copending application of Harry J. Lebherz, Serial No. 69,868, filed November 18, 1925. The details of construction of the bottle capping tool of our invention are described more particularly in Letters Patent Nos. 1,356,161, dated October 19, 1920, granted to Harry J. Lebherz, Reissue 15,285, dated February 14, 1922, granted to Harry J. Lebherz, and 70 1,421,698, dated July 4, 1922 and granted to Harry J. Lebherz.

By the construction of the bottle capping tool described herein we reduce the number of parts required in the assembly of the bottle capper and thereby decrease manufacturing costs and yet secure a bottle capping tool which may be operated in quick succession for applying crown caps to bottles, the arrangement of parts being such that the bottle capping throat and operating lever are automatically returned to an elevated position after each capping operation.

The spring means may be in the form of a bridge extending on opposite sides of a rider and engaging the segmental end of the operating lever which meshes with the vertically extending rack, normally maintaining the operating lever in an elevated position, as a result of which the bottle capping throat is normally elevated above the bottles to which crown caps are to be successively applied. The spring means may be housed between the side walls of the rider and engage the segmental end of the operating lever for maintaining the operating lever in elevated position. In order that the crown caps may be conveniently applied to the bottles we provide a spring member which maintains the crown caps in position while the rider and capping throat are elevated over the bottle and yet permits the crown cap to be pressed over the bottle during the capping operation.

Referring more particularly to the drawings, reference character 1 indicates the frame of the bottle capping tool mounted on a base 2. The frame 1 is provided with

a rack 3 on which a rider 4 is mounted for 500
slidable movement. The rider 4 consists of a plate member which is bent upon itself and the edges finally riveted as represented at 5. The plate member which constitutes the walls of the rider is in the form of an enclosure for the rack 3 and provides a pivot 6 for the operating lever 7. The rider 4 is shaped adjacent one edge as represented at 8 to embrace the sides 9 of the rack 3 so that the rider 4 is capable of reciprocatory movement along the rack 3. The lever 7 is provided with a segmental end which is toothed as represented at 10, the teeth of the lever 7 meshing with the teeth of the rack 3. The end of the lever 7 is notched as represented at 11 to receive a U-shaped bridge member 12 therein. The side walls of the rider 4 are notched as represented at 13 so that the bridge member 12 may be normally centered when the operating lever 7 is in its elevated position. The bridge member 12 extends over the side walls of the rider 4 and has portions thereof depending on opposite sides thereof as represented at 12^a and 12^b. The portions 12^a and 12^b terminate at hook members 12^c and 12^d which engage with spring members 14 and 15, respectively. The spring members 14 and 15 are provided with hook shaped ends 14^a and 15^a which extend into notches 4^a in the side walls of rider 4. The spring members 14 and 15 are balanced against each other on opposite sides of the rider and tend to maintain the U-shaped member 12 in its lowermost position and in abutment of the segmental end of the hand operated lever 7. Pressure applied to the hand operated lever 7 serves to move the rider from the position shown in Figure 1 to the position illustrated in Fig. 2 for the application of a crown cap to a bottle.

The rider 4 carries a bottle capping throat 16 which is outstruck at its top 17 and secured to the rider 4 by means of a bolt member 18. The bottle capping throat has a resilient gasket 19 therein retained in position by means of spurs 20, as more fully explained in the copending application to Harry J. Lebherz, Ser. No. 755,672, filed December 13, 1924. The bottle capping throat 16 is flared outwardly and terminates in an annular flange 21, permitting a crown cap 22 to be gripped in the capping throat for application to a bottle.

In order that the crown caps may be applied to the bottles in rapid succession, we provide a wire member 23 bent to shape as represented in Figs. 5 and 6 the wire member being secured around the peripheral flange of the bottle capping throat for retaining the crown cap 22 in position. The wire member 23 comprises a pair of parallel extending portions 24 which are bent upwardly as represented at 25 and secured over the flange 21. In effect the wire member

forms a pair of parallel extending rails along which the crown caps may be slid in succession after each application of a cap to a bottle.

In Fig. 7 we have illustrated a modified arrangement of a spring return for the rider wherein a spring member 26 extends between the lower portion of the tooth segment of the hand lever 7 in a position indicated at 27 and hooks over the rider 4 as represented at 28, normally maintaining the rider in elevated position and ready for each successive bottle capping operation.

While we have described our invention in certain preferred embodiments, we desire that it be understood that modifications may be made and that no limitations upon our invention are intended other than are imposed by the scope of the appended claims.

What we claim as new and desire to secure by Letters Patent of the United States is as follows:

1. In a bottle capper a frame having a rack, a rider slidable thereon, a lever pivoted on the rider and having a segment meshing with the rack, a capping head carried by the rider, a pair of spring members extending on opposite sides of said rider and connected to the lower extremity thereof and a bridge member connected to the upper extremity of said spring members and extending over said segment for normally elevating said lever and maintaining said rider in a position for the application of a cap to a bottle.

2. A bottle capper comprising a frame having a rack, a rider slidable thereon, a capping head carried by said rider, a lever pivoted to the rider and having a segment meshing with the rack to raise and lower the rider, a pair of spring members connected to opposite sides of the walls of said rider and a U-shaped bridge member secured to said spring members and extending over said segment for maintaining said lever in elevated position for the application of a cap to a bottle.

3. A bottle capper comprising a frame, a rider slidable on the frame, a lever pivotally mounted between the side walls of said rider and having a segment engaging the frame to reciprocate the rider, a capping head carried by the rider said segment being notched adjacent its upper extremity, a U-shaped bridge member positioned in said notch and depending on opposite sides of the walls of said rider, and spring members connected with the extremities of said U-shaped bridge member and the lower extremities of the side walls of said rider for urging said segment to a position within the limits of the walls of said rider and elevating said lever.

4. In a bottle capper a frame having a rack, a rider slidably mounted thereon, a

- lever pivoted on the rider and having a segment meshing with the rack, a capping head carried by the rider, a balanced spring device connected at opposite ends of said 5 rider and extending over said rider and providing an abutment for the segment of said lever for normally elevating said lever and maintaining said rider in a position for the application of a cap to a bottle.
- 10 5. In a bottle capper a frame having a rack, a rider slidable thereon, a lever pivoted on the rider and having a segment meshing with the rack, a capping head carried by the rider, a spring member having a pair of spiral portions extending adjacent the walls 15 of said rider and connected thereto at the ends thereof and means interconnecting the other ends of said spiral portions providing an abutment for the segment of said lever for normally elevating said lever and maintaining said rider in a position for the application of a cap to a bottle. 20

In testimony whereof we affix our signatures.

HARRY J. LEBHERZ.
